ROLLAND H. MAXSON, OF MILTON, WISCONSIN, ASSIGNOR TO THE BURDICK CORPORATION, OF MILTON, WISCONSIN, A CORPORATION OF DELAWARE

ALTERNATING CURRENT RECTIFIER

Application filed May 4, 1925. Serial No. 27,673.

This invention relates to alternating current rectifiers.

It will be explained as embodied in a rectifier particularly adapted for supplying high-pressure mercury arc lamps, such as are used in light therapy, with unidirectional current from an alternating current source.

Mercury arc lamps such as are used in light therapy for the production of actinic or ultraviolet light rays, ordinarily require a series ballast resistance whose function is to limit the current flow during the starting period when the voltage drop across the lamp is relatively low. After the vapor pressure in the lamp has increased and a condition of equilibrium or stability is reached, this ballast resistance may be used to adjust the arc voltage. Heretofore rectifiers have been employed which utilize vacuum tube or electronic valves, each of which comprises in general an evacuated or low pressure inert-gas filled vessel or tube containing two electrodes, i. e., an anode and a heated cathode. These valves, under proper operating conditions, permit current to flow through them in one direction, but prevent the passage of current in the reverse direction. Consequently, by a proper arrangement of transformer windings and valves, both waves of the alternating current may be rectified to produce a pulsating unidirectional current. These current pulsations fall to zero twice for each alternating current cycle, and since the arc lamp will not operate if the current falls below a certain minimum value, it has been the practice to employ a reactance or inductive resistance in the lamp circuit. This reactance, when the current is flowing to the lamp, causes the current pulsations to lag behind the voltage pulsations, and the current may be prevented from falling below the critical value for the lamp. In other words the reactance serves to smooth out or straighten the unidirectional current waves.

To supply rectified or unidirectional current to a mercury arc therapeutic lamp at a typical voltage of approximately 75 volts and 4.74 amperes, it has been the practice to locate the ballast resistance in the transformer secondary or lamp circuit, that is, on the load

side of the transformer, as distinguished from its line side. In order to overcome the voltage drop in the ballast resistance and reactance, it is necessary for the rectifier to deliver about 120 D. C. volts in order to provide the 75 volts across the lamp terminals. The electronic valve ordinarily employed will not operate satisfactorily when the voltage across or between its electrodes is much in excess of 75 volts. Therefore it has been the practice to employ two valves in series to rectify each half-wave or cycle in order to obtain the desired 120 volts. Thus, four valves have been required, and because the ballast resistance is located in the transformer secondary or lamp circuit, it has been necessary with the arrangement heretofore used to make the transformer large enough to carry the energy loss of the ballast resistance and cathode excitation in addition to its load current.

One of the objects of this invention is to provide an improved rectifier.

Another object is to provide an improved electronic valve type of rectifier particularly adapted for supplying mercury arc therapy lamps with unidirectional current from an alternating current source.

Another object is to provide a relatively inexpensive rectifier.

Another object is to provide a rectifier requiring a smaller number of valves than have been necessary heretofore.

Another object is to provide a rectifier wherein the capacity or size of the transformer may be reduced.

Another object is to provide a rectifier which is efficient and relatively simple.

Other objects and advantages will herein-after appear.

An embodiment of the invention particularly adapted for use in light therapy is diagrammatically shown in the accompanying drawing.

In the drawing a typical air cooled high-pressure mercury arc therapeutic lamp 5 is arranged to receive unidirectional current from an alternating current supply line 6. The details of the lamp need not be described because such lamps are well-known in the

art. In general, it comprises an evacuated quartz tube 7 containing a body of mercury 8 which serves as the cathode or negative electrode and a solid metallic anode 9. The most generally employed method of starting such a lamp is to tilt the tube until the mercury contacts with the anode, thus completing the circuit and causing the current to start flowing. Then the tube is tilted back again to separate the mercury from the anode and thus strike or draw the arc.

The improved rectifier has a transformer provided with a primary winding 10 and a secondary composed of two main sections 11 and 11' and two exciting sections 12 and 12'. A variable resistance 13 is located in the transformer primary circuit to maintain the voltage across the primary winding at the proper value and to act as ballast resistance for the lamp. The inner ends of the transformer secondary sections 11 and 11' are connected to one terminal of the lamp through a reactance 14. This reactance serves in the usual way to smooth out the waves of the pulsating rectified or unidirectional current and prevent the same from falling so low that the arc will go out or become unstable. The outer ends of the main secondary sections 11 and 11' are connected to the cathode exciting or heating circuits of electronic valves 15 and 15', respectively. Each of these valves comprises an evacuated or low pressure inert gas filled vessel or tube containing two electrodes. The operation of the valve is dependent upon the heating of the cathode or negative electrode. The cathode 16 of valve 15 is heated or excited by current from exciting secondary 12, and the cathode 16' of valve 15' is excited or heated by current from exciting secondary 12'. The anodes or positive electrodes 17 and 17' of valves 15 and 15', respectively, are connected to the cathode terminals of the mercury arc lamp.

For the production of $4\frac{1}{4}$ amperes of current at a normal operating voltage of approximately 75 D. C. volts at the mercury arc lamp terminals from a line voltage of 110 volts A. C., good results have been obtained by winding the transformer primary with 87 turns of #13 B. & S. gauge wire, and each of the main secondary sections with 112 turns of #15 B. & S. gauge wire. Thus, when the ballast resistance is adjusted to provide about 85 volts across the primary, the voltage across the two main sections of the secondary will be about 219 volts A. C. or a rectified voltage of about 75 volts. Each of the cathode exciting sections of the secondary is wound with two turns of #10 B. & S. gauge wire which will provide a maximum of about $2\frac{1}{2}$ volts across each cathode at no load.

The operation of the rectifier is as follows: The alternating voltage impressed upon the primary winding induces an alternating potential across all of the sections or windings

of the secondary. Since the excitation of the valve cathodes is dependent entirely upon the heating effect of the current flowing therethrough, the current induced in exciting secondaries 12 and 12' is not rectified but flows through the respective cathode filaments as alternating current. The heating of the cathodes renders the valves operative to permit current to flow therethrough from the anode to the cathode, although current is still prevented from flowing in the opposite direction as long as the voltage impressed across the electrodes does not exceed their break-down value, which ordinarily is about 75 volts. Consequently, during one-half wave of the alternating voltage induced in the main secondary sections 11 and 11', current will flow, for example, from the common point between the main secondary sections through the reactance 14 and lamp 5 and through valve 15 from its anode 17 to its cathode 16, and thence to the outer end of secondary section 11. During this half-wave, however, valve 15' prevents current from flowing in the opposite direction. On the next half-wave, current flows from the point between the main secondary sections through reactance 14 and lamp 5 and through valve 15' from its anode 17' to its cathode 16' and thence to the outer end of secondary section 11'. Valve 15 prevents the flow of current in the opposite direction during this half-wave. Thus the alternating current provides a pulsating unidirectional current, the frequency being twice the frequency of the alternating current. The voltage across the electrodes of the electronic valves during all load conditions is sufficiently limited to prevent injury thereto or interfere with their valve action. When the arc is not burning, however, and consequently the only current flowing in the primary circuit is that drawn by the exciting secondaries, the voltage across the valve electrodes may be sufficiently high to cause the valves to break down or pass current in the wrong direction. It has been discovered that this breaking down under no load conditions can be eliminated by putting a small load on the valves. A voltmeter V connected across the leads to the mercury arc lamp has been found to afford sufficient load under ordinary conditions.

The improved rectifier permits the elimination of two of the valves which are essential to the prior rectifiers, and yet the voltage impressed across their electrodes may be kept at safe values. Since the ballast resistance is located on the line side instead of the lamp or load side of the transformer, the transformer does not have to supply the energy lost in their resistance during operation. Also the current required to excite the valve cathodes is reduced because the number of valves is reduced. Consequently, the capacity and size of the transformer may be mate-

rially reduced. It has been found that for the ordinary therapeutic mercury arc lamp the size of the transformer may be reduced in the neighborhood of 35%. Another feature of advantage is that the maximum voltage is impressed upon the valve cathodes or filaments before the load, i. e., the lamp, is turned on, but drops to a relatively low value as soon as current is flowing between the valve electrodes. Thus the maximum voltage is impressed at a time when the valve is supposed to "pick up" or begin rectifying, but falls to a relatively low value after the current between the electrodes is flowing and when only a relatively low exciting current is required.

Although a rectifier employing only a pair of valves has been described in detail, it will be understood that a greater number may be used when higher voltages of unidirectional current are needed. However, the ratio between the number of valves used in my rectifier and the rectifier heretofore used will remain the same. That is for a given voltage my rectifier will require only half as many valves as the prior rectifiers.

I claim:

1. The combination of a mercury arc vacuum tube having a relatively low resistance at starting and a high resistance when normally operating, a valve for rectifying each half-wave of an alternating current source, a transformer and ballast resistance in the primary circuit thereof for limiting the alternating voltage impressed from the source upon the valves and automatically varying the voltage impressed on the tube as the resistance thereof changes, and a reactance interposed between the tube and the transformer to lessen the amount of the fluctuations of unidirectional current impressed on the tube.

2. In combination a high pressure mercury arc lamp having an anode and a cathode, a pair of valves connected to the lamp cathode and each permitting only alternate half-waves of alternating current to pass therethrough to the lamp, a transformer having a primary winding for connection to an alternating current source and a secondary winding which is connected at a different point to each valve and at a common point to the lamp anode, the transformer serving to reduce the voltage of the induced half-waves to a value within the rectifying range of the valves, and a ballast resistance in the circuit between the transformer primary and the source.

3. In combination a high pressure mercury arc lamp having an anode and a cathode, a pair of valves connected to the lamp cathode and each permitting only alternate half-waves of alternating current to pass therethrough to the lamp, a transformer having a primary winding for connection to an alternating current source and a secondary

winding which is connected at a different point to each valve and at a common point to the lamp anode, the transformer acting to reduce the voltage of the induced half-waves to a value within the safe rectifying range of the valves, a ballast resistance in the circuit between the transformer primary and the source, and means for preventing the breaking down of the valves when the same are subjected to voltage while the lamp is extinguished.

4. In combination a high pressure mercury arc lamp having an anode and a cathode, a pair of valves connected to the lamp cathode and each permitting only alternate half-waves of alternating current to pass therethrough to the lamp, a transformer having a primary winding for connection to an alternating current source and a secondary winding which is connected at a different point to each valve and at a common point to the lamp anode, the transformer acting to reduce the voltage of the induced half-waves to a value within the safe rectifying range of the valves, a ballast resistance in the circuit between the transformer primary and the source, and a relatively small load permanently in circuit between the valves and the lamp to prevent excessive voltage being applied to the valves when the lamp is not in service.

In witness whereof I hereunto subscribe my name this 27th day of April, 1925.
